[57] CLAIM

The ornamental design for a combined writing board and pen, as shown and described.

DESCRIPTION

FIG. 1 is a top plan view of a combined writing board and pen showing our new design, the cord on the pen is shown broken away to indicate indeterminate length; FIG. 2 is a side elevational view thereof, the pen being removed for ease of illustration; FIG. 3 is a bottom plan view thereof; FIG. 4 is an enlarged sectional view taken in the direction of the arrows along line 4—4 in FIG. 1.

FIG. 1

FIG. 2

FIG. 3

FIG. 4
